UNITED STATES PATENT OFFICE.

MARGARET O'SULLIVAN, OF PITTSBURG, PENNSYLVANIA.

DESIGN FOR A TACK.

SPECIFICATION forming part of Design No. 27,138, dated June 1, 1897.

Application filed February 27, 1897. Serial No. 625,421. Term of patent 7 years.

To all whom it may concern:

Be it known that I, MARGARET O'SULLIVAN, a citizen of the United States of America, residing at Pittsburg, in the county of Allegheny and State of Pennsylvania, have invented certain new Designs in Tacks, of which the following is a specification, reference being had therein to the accompanying drawings.

This invention relates to certain new designs in tacks, and in describing the invention in detail reference is had to the accompanying drawings, forming a part of this specification, and wherein like letters of reference indicate similar parts throughout the different views, in which—

Figure 1 is a perspective view of my new design. Fig. 2 is a top plan view of same.

The principal feature of my design resides in the head *a*, curved in outline similar to a heart shape, the tack or prong portion *b* extending downward from the meeting point or *V* of the head and provided with a pointed end *c*. 20

Having fully described my invention, what I claim is—

The design for a tack as herein shown and described. 25

In testimony whereof I affix my signature in presence of two witnesses.

MARGARET O'SULLIVAN.
